UNITED STATES PATENT OFFICE.

DRUSILLA C. McCONNELL, OF BELTON, SOUTH CAROLINA.

SEED-SEPARATOR.

1,247,433.

Specification of Letters Patent. Patented Nov. 20, 1917.

Application filed January 12, 1917. Serial No. 141,970.

To all whom it may concern:

Be it known that I, DRUSILLA CROSSON McCONNELL, a citizen of the United States, residing at Belton, in the county of Anderson 5 and State of South Carolina, have invented certain new and useful Improvements in Seed-Separators; and I do hereby declare the following to be a full, clear, and exact description of the invention, such as will 10 enable others skilled in the art to which it appertains to make and use the same.

This invention relates to a separator, for separating various types of seeds, such as cotton seeds, wheat, oats, or the like, so that 15 the imperfect and inferior seed will be separated from the perfect and more productive seeds.

Another object of this invention is to provide a separator as specified which includes 20 a supporting structure having a hopper carried thereby, which supporting structure rotatably supports a shaft, upon which shaft is mounted a foraminous rotor or drum, which rotates with the shaft, and a feed 25 screw which feeds the seed from the hopper into the drum; to provide a crank handle upon one end of the shaft for rotating the same which will cause, during the operation 30 of the separator, the seed to pass through three separate and distinct motions during its passage through the rotary foraminous drum or cylinder, namely alternately rolling, sliding and falling upon the screen, which motions are gone through with by 35 each particle of substance, or each seed many times as it passes through the cylinder or drum, bringing it in contact with the screen in many different positions, thus giving the seed an opportunity to pass through the 40 screen if it will.

With the foregoing and other objects in view, this invention consists in such novel features of construction, combination and arrangement of parts as will be hereinafter 45 more fully described, illustrated in the accompanying drawings, and claimed.

In describing the invention in detail, reference will be had to the accompanying drawings, wherein like characters designate like 50 and corresponding parts throughout the several views, and in which:

Figure 1 is a side elevation of the improved separator.

Fig. 2 is an end view of the separator, 55 Fig. 3 is a vertical section through the separator, and

Fig. 4 is a horizontal section through the separator.

Referring more particularly to the drawings, 1 designates the supporting structure of the separator as an entirety, which supporting structure includes a plurality of vertical supports 2, and horizontal supports 3, which are connected to the vertical supports 2 in any suitable manner, such as by bolts, 60 screws or the like as indicated at 4 for forming a suitable substantial support or bracing structure. The vertical supports or legs 2 are braced laterally of the supporting structure, by braces 5. The uppermost laterally extending pair of the braces 5 have bearings 6 carried thereby which rotatably support a shaft 7. The shaft 7 is rectangularly shaped in cross section, with the exception of the portions 75 which are rotatably seated in the bearings 6, and it has a crank handle 8 formed upon one end of the same.

The vertical supports 2 which are positioned at the end of the frame 1, which rotatably supports the end of the shaft which has the crank handle 8 formed thereon, extend upwardly above the upper edge of the side boards 9 and form supports for a hopper 10, the bottom 11 of which is supported 80 by the cross brace 5' and the upper edge of a board 12. The bottom 11 of the hopper is provided with a cutout portion 13 in which is mounted a trough 14. The trough 14 extends through an opening 15 which is formed 85 in the board 12. The bottom 11 of the hopper is provided with a cutout portion 13 in which is mounted a trough 14. The trough 14 extends through an opening 15 which is formed 90 in the board 12 and through the central opening 16 of the end 17 of the rotary foraminous drum 18. The rotary foraminous drum 18 comprises the inlet end 17, a plurality of longitudinally extending bracing strips 19 and a plurality of circumferentially extending circular braces 20 and 21. The brace 21 is attached to the outer end of the rotary foraminous drum 18. The mesh or screen 22 of the drum or cylinder is attached to the braces in any suitable manner, 100 and the circular braces 21 and the ring 17 are braced by suitable bracing arms 23, which are attached to the rectangular shaft 7 and radiate therefrom, being attached to the inner surface of the circular brace 21 and the ring 17 respectively, as clearly shown in 105 Fig. 4 of the drawings.

In Fig. 1 of the drawings, the mesh 22' of which the cylinder or drum is formed is constructed of three separate sections 22^a, 22^b, and 22^c, the mesh of which sections vary, 5 for instance the mesh of the section 22^a is much finer than the mesh of the section 22^b, while the mesh of the latter section is finer than the mesh of the section 22^c. This is provided for separately grading different 10 types of seeds or grain which may be passed through the device. Suitable receptacles 23^a, 23^b, and 23^c are supported by a platform 23' beneath the rotary drum 22' for receiving the separated and sorted seeds or grain from 15 the various sections of the rotary cylinder or drum 22'.

The shaft 7 has a worm or auger feed screw 25 mounted thereon which extends through the hopper 10 and part way into 20 the cylinder 22 for feeding the seed through the trough 14 into the rotary cylinder.

When the seeds, such as cotton seeds or the like are placed within the hopper 10, and the rotation of the shaft 7 through the medium 25 of the crank handle 8 which is formed thereon will rotate the feed screw or auger 25, and feed the seed from the hopper through the openings 15 and 16 into the rotary foraminous drum or cylinder, which will 30 also be rotated by the rotation of the shaft 8 through the medium of the braces 23 which connect the outer foraminous surface of the drum or cylinder to the shaft 7. During the rotation of the foraminous cylinder or drum, 35 the seeds will travel longitudinally therethrough, and be moved in a rotary manner, fall downwardly diametrically through the drum, and travel longitudinally therethrough, which will present the seeds at several different angles to the openings in the 40 mesh work 22 of the cylinder, allowing all of the small and inferior seeds to fall through the openings upon the floor beneath the cylinder, while the perfect seeds will 45 travel through the entire length of the cylinder and out through its open delivery end.

When using the drum as illustrated in Fig. 1 of the drawings, the smallest or finest

seeds will fall through the mesh of the section 22^a, and the next finest seeds through 50 the mesh of the section 22^b, and slightly larger seeds will fall through the mesh of the section 22^c, while the largest and most perfect seeds will travel out through the open end of the cylinder. 55

From the foregoing description taken in connection with the accompanying drawings, the advantages of construction and of the method of operation of the improved seed separator will be readily apparent to those skilled in the art to which this invention appertains, and while in the foregoing description, the principle of the operation of this invention has been described together with various features of construction, it is 60 to be understood that certain minor features of construction, combination and arrangement of parts may be altered to suit practical conditions provided such alterations are comprehended within the scope of what 65 is claimed.

What is claimed is:

In a seed separator, a supporting structure, a shaft rotatably carried by said supporting structure, a foraminated drum carried by said shaft, said drum comprising a plurality of longitudinally extending circumferentially spaced braces having their ends secured to said shaft, said braces having their portions intermediate their longitudinally extending portions and their ends extending inwardly toward the axis and transverse center of the foraminated drum, a plurality of circular braces attached to said longitudinal braces at spaced intervals, 80 a cylindrical screen attached to said braces, a circular end plate mounted in the end of said drum and provided with a central opening, the opposite or outlet end of said drum being open. 90

In testimony whereof I affix my signature in presence of two witnesses.

DRUSILLA C. McCONNELL.
